CLAIM

The ornamental design for a tub drain cover, as shown and described.

DESCRIPTION

FIG. 1 is a top right perspective view of a tub drain cover showing my new design;

FIG. 2 is a top left perspective view thereof;

FIG. 3 is a bottom left perspective view thereof;

FIG. 4 is a front view thereof;

FIG. 5 is a back view thereof;

FIG. 6 is a top view thereof;

FIG. 7 is a bottom view thereof;

FIG. 8 is a left view thereof; and,

FIG. 9 is a right view thereof.

The broken lines shown in FIGS. 1-4 and 6-9 illustrate portions of the tub drain cover that form no part of the claim.
